UNITED STATES PATENT OFFICE

LEANDER G. YEATON, OF AMESBURY, MASSACHUSETTS, ASSIGNOR TO AMESBURY BRASS & FOUNDRY COMPANY, OF AMESBURY, MASSACHUSETTS, A CORPORATION OF MASSACHUSETTS

WINDSHIELD

Application filed March 4, 1931. Serial No. 519,956.

My invention relates to wind-shields, particularly adapted for use on boats.

The invention will be best understood from the following description when read in the light of the accompanying drawings of one embodiment of the invention, the scope of which latter will be more particularly pointed out in the appended claims.

In the drawings:—

Fig. 1 is a perspective view of a boat equipped with a wind-shield constructed according to the invention;

Fig. 2 is an elevation of the wind-shield according to Fig. 1, with the panels moved to lie in the same plane;

Fig. 3 is a fragmentary, longitudinal section of one of the corners of the end panels showing a detail;

Fig. 4 is a fragmentary, longitudinal section of the frame for the wind-shield, with parts broken away; and

Figs. 5 to 10 inclusive are sections on the lines 5—5, 6—6, 7—7, 8—8, 9—9 and 10—10 respectively of Figs. 2 and 4.

Referring to the drawings, the wind-shield constituting the submitted embodiment of the invention comprises a front panel 1 and side or end panels 3, the latter as shown being triangular and each having an end edge operatively hinged to the adjacent end edge of the front panel. With this construction the wind-shield may be applied to a boat, as illustrated by Fig. 1, in which figure the lower or bottom edges of the three panels are shown in contact with the deck 5 of the boat. By placing the end panels at different angles to the front panel the inclination of the latter may be varied and the wind-shield may be adjusted to boats of different dimensions, as for example cockpits 7 of different widths, which commonly are surrounded at the edge of the deck and wash-board by a combing 9.

As illustrated, the front panel 1 comprises a frame for supporting a pane 11 of glass or other transparent material, said frame as herein shown comprising a top molding 13, a bottom molding 15, and opposite side or end moldings 17, said moldings at their ends being mitered as indicated at 19 and abutting

the mitered ends of adjacent moldings to form the corners of the frame.

Herein, the top molding 13 of the front panel is formed of sheet metal to provide a hollow bar having a top portion 21 (Fig. 5) terminating in downwardly directed, longitudinally extending parallel portions 23, the top portion 21 conforming to the surface of a cylinder. At their lower ends the longitudinally extending portions 23 are folded back against the inner sides as indicated at 25, the upper ends of said portions 25 being connected by a transverse portion 27. By this construction grooves 29 are formed for receiving the upper edge of the pane 11, said edge conveniently being received in the groove 31 of a channel-shaped strip or gasket of rubber 33 fitting the groove 29.

The lower molding 15 of the front panel, as best illustrated in Figs. 2, 4 and 6, comprises a hollow, bar-like structure formed of sheet metal to present the opposite parallel walls 35. At its upper edge the molding is formed in a manner similar to that described in connection with the lower edge of the top molding 13 to present a groove 37 for receiving a gasket 39 and the lower edge of the pane. At the lower edge of the molding the side walls are turned inward as indicated at 41 to provide bottom wall portions which extend from each side wall 35 part way across the space separating said walls. At the inner edges of these bottom wall portions the metal is turned upward to form portions 43 inclined in each instance toward the adjacent side wall 35, the upper edges of the portions 43 being connected by a wall 45 in spaced relation to the bottom wall 47 of the groove 37. In the dovetail-shaped groove formed by the portions 43 and 45 is received the wedge-shaped portion 49 of a rubber strip or gasket 51, which latter projects below the molding 15 and is adapted to contact with the deck 5 of the boat when the wind-shield is installed.

The end moldings 17 of the front panel, as best shown by Figs. 4 and 8, are similar in shape to the bottom molding 15, so as to provide grooves 53 and 55. The grooves 53 receive the gaskets 57 and the adjacent end

edges of the pane 11, while the grooves 55 receive gaskets 59 of the same shape as the gasket 51, the gaskets 59 being adapted to contact with the adjacent edges of the end panels.

For holding the moldings 15 and 17 in assembled relation the frame is provided at its corners with angle-pieces, the opposite legs 61 of which latter are received in the interior 10 passages of the moldings, as clearly illustrated in Figs. 2, 7 and 8, the moldings conveniently being secured to said legs by the screws 63 and rivets 65.

The end panels 3, as illustrated, each comprise the end molding 67, the bottom or base molding 69, and upper molding 71, these moldings being mitered at their ends as indicated at 73, each end of each molding abutting the adjacent mitered end of the adjacent 20 molding.

As will be obvious from a comparison of Figs. 5 and 8, the end molding 67 of each end panel 3 in cross-section is exactly similar to the top molding 13 of the front panel, so as 25 to provide for each end molding a portion 75 conforming to the surface of a cylinder, and also to provide a groove 77 for receiving the end edge of a pane of glass 79 and cooperating rubber gasket 81.

30 The bottom or base molding 69 and top molding 71 of each end panel, as best illustrated in Figs. 4 and 9, are of cross-sectional shape similar to the bottom molding 15 of the front panel, except that no groove is provided for the projecting rubber gasket 51. The molding 69 and 71 therefore provide 35 grooves 83 for receiving the adjacent edges of the pane of glass 79 and cooperating rubber gaskets 85.

40 For holding the moldings 67, 69 and 71 of the end panels in assembled relation, the frame is provided at its upper corner with an angle-piece having the legs 87 received in the interior cavities of the adjacent moldings, 45 said legs being secured to said moldings by the screws 89. At the lower corner adjacent the front panel is provided an angle-piece having the legs 91 received in the interior channels of the moldings, the lower leg having the lug 93 which projects from the end 50 of the frame and is provided with the perforation 95 for receiving a screw or bolt for securing the end panel at its bottom edge to the deck of the boat. The moldings 71 and 60 69 at the corners of the end panels remote from the front panel are held in assembled relation by angle-pieces having legs 97 (Fig. 3) fitting the interior channels of the moldings and secured thereto by rivets 99 and 65 screws 101. This corner of each end panel is provided with a member having a projecting lug 103 which has a perforation 105 for receiving a screw or the like for securing the end panel at its bottom edge to the deck.

85 The member which carries the lug 103 has

side pieces 107 (Fig. 2) respectively lying at the front and rear sides of the frame, the side pieces being connected at their upper edges by a transverse part 109 so as to form a channel for receiving the corner of the frame. The rivet 99 extends from the exterior of one side piece 107 to the exterior of the other, while the screws 101 extend through the transverse portion 109 of the member so as to secure all the parts adjacent 75 the corner of the frame in assembled relation.

As shown, the front panel 1 is connected to the two end panels by angle-members 111 at the upper corners of said panels, said angle-members having legs 113 of cylindrical cross-section received in the cylindrical portions 21 and 75 of the top molding 13 of the front panel and end moldings 67 of the end panels, the construction being such as 80 to hinge the end panels to the front panel for making the wind-shield adjustable to the boat and for permitting the front panel to hinge about its upper edge so that the wind-shield may be opened and closed. When 90 the front panel is closed the rubber gaskets 59 at opposite ends thereof bear against the end moldings 67 of the end panels as illustrated in Fig. 8.

As shown, the horizontal legs 113 of the angle-members 111 are in the form of sleeves, said legs being split longitudinally as indicated at 115 (Figs. 4 and 7). At each end of the upper edge of the front panel a wing-screw 117 has its shank 119 screw threaded through the adjacent wall of the sleeve formed by the horizontal hollow leg 113, the end of the shank of the wing-screw bearing against the inner opposite wall of the sleeve. By this construction the sleeve may be spread 105 to clamp the front panel in position when it is raised. For permitting opening and closing of the front panel the upper molding 13 thereof adjacent each screw 117 is formed with a 110 arcuate circumferential slot 121 through 115 which the shank 119 of the screw passes.

It will be understood that wide deviations may be made from the embodiment of the invention herein disclosed without departing from the spirit of the invention.

Claims:

1. An adjustable wind-shield having, in combination, a front panel, end panels, and means connecting said panels in assembled relation with the end edges of said end panels parallel and adjacent to the end edges of said front panel, said means providing for rotation of said front panel about its upper edge.

2. An adjustable wind-shield having, in combination, a front panel, end panels, and means connecting said panels in assembled relation with the end edges of said end panels parallel and adjacent to the end edges of said front panel, and means providing for rotation of said front panel about its upper edge.

and for rotation of said end panels about their end edges.

3. An adjustable wind-shield having, in combination, a front panel, end panels, means on which said front panel is rotatable about its upper edge, said means having portions parallel to the end edges of said front panel upon which said end panels are rotatable about their adjacent edges.

10 4. An adjustable wind-shield having, in combination, a front panel, end panels, an angle member at each upper corner of said front panel, said angle members having legs on which said front panel is rotatable about its upper edge, and having other legs upon which the adjacent end panels are rotatable about their end edges.

15 5. An adjustable wind-shield having, in combination, a front panel, opposite end panels, said panels being so shaped that if laid in the same plane with the end edges of said end panels parallel to the end edges of said front panel the lower edge of the latter will be at interior angles of between 90 and 180 25 degrees to the lower edges of the former, and means for securing said panels in assembled relation providing for rotation of said front panel about its upper edge and for rotation of said end panels about their end edges.

20 6. An adjustable wind-shield having, in combination, a front panel, opposite end panels, said panels arranged with their adjacent end edges in substantially parallel relation, panel connecting means to which the end 25 edges of said end panels are hingedly secured and to which the upper edge of said front panel is hingedly secured, and means having provision for securing said end panels to a support whereby they may support said front 30 panel for swinging movement about its upper edge.

35 7. An adjustable wind-shield having, in combination, a substantially rectangular front panel, opposite end panels, the latter 40 having end edges and bottom edges at acute angles to each other, and panel connecting means to which the end edges of said end panels are hingedly secured and to which the upper edge of said front panel is hingedly secured.

45 In testimony whereof, I have signed my name to this specification.

LEANDER G. YEATON.
